UNITED STATES PATENT OFFICE.

CHARLES R. HAWKINS, OF NEWPORT, KENTUCKY, ASSIGNOR OF ONE-HALF
TO JOHN I. MARTIN, OF SAME PLACE.

COMBINATION-TOOL OF PRECISION.

SPECIFICATION forming part of Letters Patent No. 651,037, dated June 5, 1900.

Application filed February 26, 1896. Serial No. 580,889. (No model.)

To all whom it may concern:

Be it known that I, CHARLES R. HAWKINS, a citizen of the United States, and formerly a resident of the city of Cincinnati, in the county of Hamilton and State of Ohio, but now a resident of the city of Newport, in the county of Campbell and State of Kentucky, have invented certain new and useful Improvements in Combination-Tools of Precision, of which the following is a specification.

The several features of my invention and the various advantages resulting from their use conjointly or otherwise will be apparent from the following description and claims.

15 In the accompanying drawings, making a part of this specification, and in which similar letters of reference indicate corresponding parts, Figure 1, Sheet 1, is a side elevation of my combination-tool. Fig. 2 is a side 20 elevation of the square, the other tools having been removed therefrom. Fig. 3 is a view of the square and the scale set therewith, so as to form a combined tool called the "center-square." Fig. 4 is an elevation of the 25 square and the scale set in a position which forms a combination-tool called the "T-square." Fig. 5 is an elevation of the square and of the scribe combined therewith in such a position as to form a combination-tool called 30 the "depth-gage." Fig. 6 is an edge elevation of the tool shown in Fig. 5. Fig. 7 is an elevation of the square and of the scribe set in a certain position to illustrate the use of such combined tool in ascertaining whether 35 a hole is being drilled at the desired angle. Fig. 8, Sheet 2, is an elevation of the frontside of the square and of the level and illustrating how to get a right or left hand angle by means of it and also illustrating its position 40 when it is to be used for certain purposes—as, for example, setting a door at the right-hand jamb. Fig. 9 is an elevation of the square and of the level set in such a manner as to hang a door at the left-hand jamb. Fig. 45 10 is an edge view of the tool as shown in Fig. 9, that edge being shown which faces toward the left in Fig. 9. Fig. 11 is a repetition, on a larger scale, of the combined tool as shown in Fig. 1, a portion of the same at 50 the left-hand being broken away to economize room and set next to Fig. 12 to enable lat-

ter to be the more easily understood. Fig. 12 is a vertical central transverse section in the plane of the dotted line 12 12 of Fig. 11, that face of the section being seen which faces toward the right hand of Fig. 11. 55

A indicates the thin flat square of a peculiar, novel, and advantageous shape, viz: Its general shape is that of a triangle of which the long side or hypotenuse is indicated by the character A² and the other two sides by the respective characters A³ and A⁴. In the side A⁴, I cut or form a right-angled recess, one of whose sides, B², is parallel to the line of the hypotenuse A² and the other side, B³, 65 is at right angles to the said hypotenuse. Such formation qualifies the square to be used as an inside and outside square and also gives the carpenter or scribe a convenient tool for scribing inside and outside angles. 70

My combination - tool when arranged as shown in Fig. 3 becomes a center-square. In this the scale C is set as shown in this Fig. 3, the longitudinal lines of the scale being parallel to the side A³ of the square A. The projection of the scale C beyond the hypotenuse—viz., side A² of the square—is of benefit, as a rule, to enable a workman when boring a hole to ascertain whether the hole is being bored at the desired angle in reference 80 to that surface of the thing bored at which the hole begins. It is to be noted that the scale can be set at any desired angle with reference to any of the sides A² A³ A⁴, as desired. By setting the scale at a right angle to one of 85 the sides of the square, as A³ or A², (see Fig. 4,) the combination is converted into a T-square and can be used as such. This combination is qualified to be used as a depth-gage, (see Figs. 3 and 4,) and this can be accomplished by moving the scale back and forth and setting it to project beyond the square the depth desired. By removing the scale C from the square A and setting the scribe on the square at any desired side of 95 the same the tool becomes a scribe or scratch, substantially as shown in Fig. 5. By moving the scribe in or out of its holder, and thereby lengthening it as to a given side of the square, the marks for work to any desired width can 100 be made. By altering the position of the scribe and bringing its rear end to a straight

side of the square, substantially as shown in Fig. 7, one can employ the rear end of the scribe as an angle-gage to determine whether a hole is bored correctly at a given angle. 5 D² indicates the scribing-point of the scribe.

Fig. 8 illustrates the mode in which the combination of the square and the level L are combined. When set in one position, it gives a right-hand angle and in a certain other position gives a left-hand angle, and the tool can thus respectively be used to adjust and hang a door to a right-hand jamb (see Fig. 8) 10 or to a left-hand jamb, (see Fig. 9,) as the case may be. Obviously the level can be so set in relation to the square as to enable other articles to be located at a given angle in relation to a vertical line. By removing the square from the level the latter can be used as an ordinary level. The following important feature of construction is to be carefully noted. 15 The scale is held in a rotatable device E, centered in the square A and turning therein. This device is for the purpose of obtaining the greatest benefits of the square A and the tools combined therewith, and is therefore located so that its axial center is located in a median straight line drawn from the point where the sides A³ and A⁴ meet to the side A² and making a right angle with the latter. 20 Such location enables the scale or the scribe or level, as the case may be, to be rotated at a central point in relation to the square A, as seen.

The preferred mode of enabling the rotatable device E to hold and turn with the tools to be combined with the square is as follows: The thumb-screw E² has below it a broad concentric disk E³, containing two undercut recesses E⁴ and E⁵, the recess E⁴ of a size to 35 take most of the thickness of the scale C and the recess E⁵ adapted to receive most of the thickness of the scribe D. The shank ES of the thumb-screw E² passes through the square and is on that side duly held by a nut EN. A washer EW, concentric with the shank ES, is located on the latter and lies on the square next below the disk E³, subject to the insertion of the scale C or scribe D, or both, between the said flange and washer. 40 When either said scale or said scribe, or both, are in place in their respective recesses and between the flange and the washer, the thumb-nut EN is tightened, and either or both of the said tools, as the case may be, is held in 45 place tightly and against the square.

Upon the face of the square and around the thumb-nut is placed an arcual line or circle of graduations F, and in connection therewith a suitable mark or graduations are placed on the disk E³ of the thumb-screw. 50 By these means the scale and the scribe can be respectively correctly set in proper location in reference to the square as they are to be used. The thumb-screw is then tightened, 55 pressing the scale or the scribe against the washer, and thus compressing the tool between the flange of the thumb-screw and the

square. The tool can be readily withdrawn by loosening the thumb-screw.

The relation of the recess B to the square A in order that the scale may, in connection with the square A, operate as a center-square, as shown in Fig. 3, is as follows: The recess is so cut or formed that when the left edge C² of the scale C is exactly in the mid-point 70 H between the respective outer ends BL and BR of the sides B² and B³ the inner end IEB of side B² will just touch or end at the extended plane of that edge of the scale which is toward the hypotenuse A². Thus a competent working center-square is secured.

The level L has a flange L², and the end of shank ES of the thumb-screw passes through the flange L², and the nut EN on the thumb-screw enables the flange L² of the level L to 85 be tightened between the said nut and the square and set in any desired position as to the square. Graduations LS on that face of the square next to the level, marked in an arc around the axis of thumb-screw shank, 90 and graduations EN³ on the flange L² of the level enable the latter to be properly located with reference to the square before the thumb-screw and nut set it there.

It will be observed that the washer EW 95 has an upturned flange EW², which, in connection with the recess E⁴ of the thumb-nut flange, operates to hold and steady the scale when set by the tightening of the thumb-screw.

As will be observed, the entire tool is remarkably compact, simple of construction, and easy of adjustment. It is, moreover, economical of manufacture.

When desired, the thread on the screw-shank ES may engage a screw-thread in the square, and this will obviously be desirable when the level L is dispensed with. By omitting the nut EN and that part of the shank ES which projects through and beyond the square the latter can be laid flat for its entire extent.

What I claim as new and of my invention, and desire to secure by Letters Patent, is—

1. In a right-angled triangular piece, the right-angled recess B, located in one of the sides of the right angle and leaving those portions of the said side at each side of the recess equal, the recess B stopping short of the center, and the adjustable scale-holding device and the scale set therein, which latter when set as a center-square, has one edge at a central point between the points BR and BL, and also in the coincident plane of the corner I E B, and forming an acute angle with the hypotenuse equal to an opposite acute angle formed by the scale and that side of the recess B, which is parallel to the hypotenuse, substantially as and for the purposes specified.

2. In combination, the graduated triangular piece, and the measuring or marking tool, and the graduated level L with holding-flange L², and the double thumb-screw having the

thumb-piece E² on one side of the square, and a screw-shank, and the recessed washer, receiving said measuring or marking tool, and the washer EW, the latter having the up-turned flange EW², substantially as and for the purposes specified.

3. In combination, the graduated triangular piece, and the measuring or marking tool, and the graduated level L with holding-flange L², and the double thumb-screw having the thumb-piece E² on one side of the square, and a screw-shank, and the recessed washer, receiving said measuring or marking tool, and the washer EW, the latter having the up-turned flange EW², and the thumb-piece EN

engaging the screw-shank of the thumb-nut E², and the level L located on that side of the square which is opposite where nut E² and washer EW, and the marking and measuring tools are located, the thumb-nut EN being 20 on the same side of the said triangular piece and in connection with the thumb-screw E², holding all the parts aforesaid in place, relative to the square, substantially as and for the purposes specified.

CHARLES R. HAWKINS.
